UNITED STATES PATENT OFFICE.

CHARLES A. OBENCHAIN, OF WASHINGTON, DISTRICT OF COLUMBIA.

CURTAIN-FIXTURE.

SPECIFICATION forming part of Letters Patent No. 691,799, dated January 28, 1902.

Application filed April 23, 1901. Serial No. 57,132. (No model.)

To all whom it may concern:

Be it known that I, CHARLES A. OBENCHAIN, a citizen of the United States, residing at Washington, in the District of Columbia, have 5 invented certain new and useful Improvements in Curtain-Fixtures; and I do hereby declare the following to be a full, clear, and exact description of the invention, such as will enable others skilled in the art to which it applies 10 pertains to make and use the same.

My invention relates to improvements in curtain-fixtures, and has for its object to provide a housing or hood for the curtain in a novel manner, as hereinafter described and 15 claimed, so as to form a protection for the curtain and at the same time to form an ornament for the room.

With this object in view the invention consists, substantially, in the novel construction, 20 combination, and arrangement of parts hereinafter fully described, and particularly pointed out in the appended claims.

I attain these objects by the mechanism illustrated in the accompanying drawings, 25 in which—

Figure 1 shows a perspective view of a window with my improvement attached. Fig. 2 shows a cross-section on the line $x-x$ of Fig. 1. Fig. 3 shows the interior of the housing. 30 Figs. 4 and 5 show modified forms of brackets.

In the drawings, A represents a hood or housing adapted to fit loosely over the roll of a window-curtain or other article similarly used, inclosing it from end to end, except 35 along the rear side. The hood describes a little more than a half-circle in cross-section, as shown in Fig. 2, the half-cylinder thus formed being closed at the ends. The ends, however, may be formed in any suitable design. It may be made of tin, brass, wood, or other suitable material and may be as cheap or as expensive as the taste may dictate. Within the hood near each end is a longitudinal track a, formed of sheet metal, 40 preferably, and having flanges a', adapted to receive the lug or bearing b of the bracket B. These tracks are secured in any usual

manner. They are made several inches in length, so as to receive brackets, which may be fixed at varying distances apart. In this 50 manner the hood may be adjusted to windows of different sizes.

The bracket is a modification of the ordinary curtain-bracket and is constructed by providing the lug b, so as to form a bearing 55 for the track a.

By reference to Fig. 2 it will be seen that the curtain C will roll unobstructed back of the hood, where it may be concealed and protected from dust. 60

The hood is placed in position by sliding the lug b of one bracket into the outer end of one track, while the lug of the other bracket is passed into the inner end of the corresponding track. 65

I thus provide a cheap, durable, and easily-adjustable housing for curtains and similar articles which at once serves as a protection, conceals from view the less-sightly portions, and becomes itself an attractive ornament. 70

What I claim as new, and desire to secure by Letters Patent, is—

1. In a curtain-fixture, a hood, provided with longitudinal holding-tracks, and brackets having lugs adapted to engage in said 75 tracks, substantially as specified.

2. In a curtain-fixture, a hood composed of a single member and provided interiorly, with tracks, brackets adapted to engage in said tracks and whereby said hood may be adjusted to different-sized windows, substantially as specified. 80

3. In a new article of manufacture, a hood composed of one member, and provided interiorly with holding-tracks, and brackets 85 having lugs adapted to engage in said tracks, substantially as specified.

In testimony whereof I have affixed my signature in presence of two witnesses.

CHARLES A. OBENCHAIN.
